UNITED STATES PATENT OFFICE.

EUGENE HIGGINS, OF JACKSON, MICHIGAN, ASSIGNOR OF ONE-HALF TO DEAN G. KIMBALL, OF JACKSON, MICHIGAN.

GARAGE OR STORAGE-BUILDING.

1,321,100.

Specification of Letters Patent. Patented Nov. 11, 1919.

Application filed July 1, 1918. Serial No. 242,720.

To all whom it may concern:

Be it known that I, EUGENE HIGGINS, a citizen of the United States, residing at the city and county of Jackson and State of Michigan, have invented certain new and useful Improvements in Garages or Storage-Buildings, of which the following is a specification.

This invention relates to improvements in 10 garages or storage buildings.

The main objects of this invention are:

First, to provide an improved garage or storage building of large capacity.

Second, to provide an improved garage or 15 storage building adapted for the housing of motor vehicles which has the equivalent of several stories without the use of elevators.

Third, to provide an improved garage or storage building which permits of a motor 20 vehicle being driven to or from its allotted space by the driver without the service of an attendant.

Further objects, and objects relating to 25 structural details, will definitely appear from the detailed description to follow.

I accomplish the objects of my invention by the devices and means described in the following specification. The invention is clearly defined and pointed out in the claims.

30 A structure which is a preferred embodiment of my invention is clearly illustrated in the accompanying drawing forming a part of this specification, in which:

Figure I is a detail front elevation of a 35 building embodying the features of my invention.

Fig. II is a horizontal section thereof on a line corresponding to line 2—2 of Fig. III.

Fig. III is a detail vertical section on a 40 line corresponding to line 3—3 of Fig. II.

Fig. IV is a horizontal section corresponding to that of Fig. II, showing another embodiment of my invention.

Fig. V is a horizontal section similar to 45 Figs. II and IV showing still another embodiment of my invention.

In the drawing, similar reference characters refer to similar parts throughout the several views.

50 Referring to the drawing, the outer wall 1 is preferably circular although that is not an arbitrary requirement. I provide partition walls 2 and 3, also preferably circular and concentric to the outer wall. On the

outside of the partition wall 2 I provide an 55 upward spiral driveway 4 having an entrance 5 through the doors 6. Between the walls 2 and 3 I provide a downward spiral driveway 7 having an exit 8 to the street.

Between these entrances and exit portions 60 of the driveways is a room 9 which may be employed for display purposes or offices or otherwise as may be desired. This room has door openings 10 communicating with the entrance and exit. At the right of the entrance driveway is a room 11 which is adapted 65 for storage or any other suitable purpose.

I provide a series of spirally disposed stalls or storage spaces 12 having horizontal 70 floors, the side walls 13 of which are in the embodiment shown in Fig. II tangentially disposed relative to the upward driveway 4 facilitating entrance to and exit from these stalls as sharp turns are not required for entrance or exit.

The outer partition wall 2 has door openings 14 therein affording access from the upward driveway to the downward driveway.

The space within the inner partition wall 80 3 has horizontal floors 15, the inner wall having door openings 16 opposite the door openings 14 affording access to these rooms or spaces.

In the modification shown in Fig. IV, the 85 spiral upward driveway 4' is located between the series of stalls or storage spaces and it is found that this is of advantage where the size of the building will permit, a considerable storage space being secured 90 by a relatively small increase in the dimensions of the building. In such a construction a passageway 17 is left opposite the door openings 14.

In the modification shown in Fig. V the 95 upward driveway 4'' is adjacent the outer wall, the storage spaces or stalls being within the upward driveway. This is of advantage in certain situations.

With the arrangement illustrated and described I secure a structure especially adapted as a garage having a large capacity and one which avoids the use of elevators as well as one in which it is entirely practicable for the ordinary driver to drive the car to his 105 particular space or stall, all cars being accessible. An attendant, who is ordinarily necessary where cars are parked in a block

on the floor of a room, not being here required.

I have shown windows 18 as being spirally arranged. They may if desired be arranged 5 in a horizontal series, and the building thus made to conform more closely to the common type of building in exterior appearance.

The exterior walls may be made rectangular or otherwise as desired although the 10 circular walls shown are very practical.

I have not attempted to describe other adaptations and modifications which I contemplate as I believe the disclosure made 15 will enable those skilled in the art to which my invention relates to embody or adapt the same as may be desired.

Having thus described my invention, what I claim as new and desire to secure by Letters Patent is:

1. A building having a circular outer wall, a continuous spiral upward driveway, a continuous spiral downward driveway within said upward driveway, circular partition walls one of which is between the driveways and the other within the inner driveway, and spirally disposed stalls each 25 opening into said upward driveway, the floors of said stalls being horizontal, their side walls being disposed tangentially of the upward driveway, said partition walls having door openings therein affording access between the upward and downward driveways and with the space within the inner of 30 the partition walls, such space having floors on a level with the driveways at said door openings.

2. A building having a circular outer wall, a continuous spiral upward driveway, a continuous spiral downward driveway within said upward driveway, circular partition walls one of which is between the driveways and the other within the inner driveway, and spirally disposed storage 40 spaces each opening into said upward driveway, said partition walls having door openings therein affording access between the upward and downward driveways and with the space within the inner of the partition walls, such space having floors on a level with the driveways at said door openings.

3. A building having an outer wall, a continuous spiral upward driveway, a continuous spiral downward driveway within 45 said upward driveway, partition walls one of which is between the driveways and the other within the inner driveway, and stalls opening into said upward driveway, the floors of said stalls being horizontal, their side walls being disposed tangentially of the upward driveway, said partition walls having door openings therein affording access between the upward and downward driveways and with the space within the inner of 55 the partition walls, such space having floors

on a level with the driveways at said door openings.

4. A building having an outer wall, a continuous spiral upward driveway, a continuous spiral downward driveway within said upward driveway, partition walls one of which is between the driveways and the other within the inner driveway, and storage spaces each opening into said upward driveway, said partition walls having door openings therein affording access between the upward and downward driveways and with the space within the inner of the partition walls, such space having floors on a level with the driveways at said door openings. 70

5. A building having an outer wall, a continuous spiral upward driveway, a continuous spiral downward driveway within said upward driveway, a partition between the driveways, and spirally disposed stalls each opening into said upward driveway, the floors of said stalls being horizontal, their side walls being disposed tangentially of the upward driveway, said partitions having door openings therein affording access between the upward and downward driveways. 75

6. A building having an outer wall, a continuous spiral upward driveway, a continuous spiral downward driveway within said upward driveway, a partition between the driveways, and spirally disposed storage spaces each opening from said upward driveway, said partitions having door openings therein affording access between the upward and downward driveways. 90

7. A building having a continuous spiral upward driveway and a continuous spiral downward driveway, a partition wall between said driveways, and a series of spirally disposed storage spaces on each side of one of said driveways, said partition wall having door openings therein affording access from one driveway to the other. 100

8. A building having a continuous spiral upward driveway and an independent continuous spiral downward driveway, there being means of access from one driveway to the other at intervals, and a series of spirally disposed storage spaces on the outer side of one of said driveways, each storage space opening directly on the driveway. 110

9. A building having a continuous spiral upward driveway and an independent continuous spiral downward driveway, there being means of access from one driveway to the other at intervals, and a series of spirally disposed storage spaces on the inner side of one of said driveways, each storage space opening directly on the driveway. 120

10. A building having a continuous spiral upward driveway, an independent spiral downward driveway arranged one within the other, there being means of access from one driveway to the other at intervals, and 130

spirally arranged storage spaces each opening upon one of said driveways the walls of which are tangential so that entrance thereto or exit therefrom may be had without a 5 sharp turn.

11. A building having a continuous spiral upward driveway and an independent continuous spiral downward driveway, and a series of spirally disposed storage spaces

each opening directly upon one of said 10 driveways for entrance and exit.

In witness whereof I have hereunto set my hand and seal in the presence of two witnesses.
